UNITED STATES PATENT OFFICE.

JAMES ROLLAND ELLIOTT, OF ST. LOUIS, MISSOURI, ASSIGNOR OF ONE-HALF
TO GEORGE HERMANN WILSON, OF SAME PLACE.

RAILROAD-SPIKE.

SPECIFICATION forming part of Letters Patent No. 613,364, dated November 1, 1898.

Application filed December 31, 1897. Serial No. 664,911. (No model.)

To all whom it may concern:

Be it known that I, JAMES ROLLAND ELLIOTT, a citizen of the United States, residing at St. Louis, in the State of Missouri, have invented a new and useful Railroad-Spike, of which the following is a specification.

One of the chief causes of rails spreading and resulting in loss and damage to life and rolling-stock is the loosening of the spikes which hold the rails to the ties. Many and various have been the attempts to overcome this difficulty, the most common being to tooth or serrate the sides of the spikes with the intent of securing a positive engagement between the spikes and the timber into which they are driven. This toothing or serrating of the spikes' sides only partially obviates the difficulty, as the spring or elasticity of the disturbed fibers of a tie when driving a spike home is partially destroyed, the fibers becoming set by being alternately compressed by the series of teeth successively acting thereon. By this invention a positive lock is secured between the spike and the tie and the spring or natural tendency of the separated fibers to regain a natural position is not destroyed, and the interlocking action and friction between the spikes and tie result in securely and firmly holding the spikes against accidental withdrawal after being driven home.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a perspective view of a spike embodying the vital features of this invention. Fig. 2 is a cross-section thereof, looking toward the head. Fig. 3 is a perspective view of a modified form of spike. Fig. 4 is a cross-section of the modification.

Corresponding and like parts are referred to in the following description and indicated

in all the views of the drawings by the same reference characters.

In its general outline the spike has an ordinary profile, being pointed at one end, headed at the opposite end, and having the sides straight and slightly convergent toward the point in the ordinary manner. The sides 1 of the spike may be flat and straight throughout their length and breadth or they may be provided with longitudinal depressions 2, having their origin a short distance from the head 3 and terminating at the point. The depressions 2 increase in depth toward a medial line, reckoning from the longitudinal edges of the sides 1, and the end portions of the depressions gradually contract in width and depth and vanish in the respective sides of the spike. The depressions may have any form in transverse section; but it is preferred to make them angling, as clearly indicated in Fig. 4, and the purpose of these depressions is to receive the fibers which spring therein, whereby the spike is prevented from turning in its opening when subjected to torsional strain.

The front and rear sides of the spike are similarly formed and are provided with parallel V-shaped grooves 4, separated by a V-shaped rib 5. The parallel or companion grooves 4 communicate a short distance from the point, forming a shoulder 6, which is rounding, and these grooves are deeper at the pointed end of the spike than at the headed end, and their terminal portions curve outwardly in opposite directions, as indicated by 7, whereby they present a finished appearance, and the fibers of the tie are deflected to insure a close joint and tight fit of the upper portion of the spike in its opening. The grooves 4 have their origin a short distance from the head of the spike and gradually deepen toward and terminate a short distance from the point. As a result of this formation of the grooves 4 the V-shaped ribs 5 converge toward their lower ends, thereby leaving the spike stouter at its upper end, which is necessary to enable it to withstand the blows rained thereon when driving it down into the tie. While it is preferred to have the front and rear sides of the spike provided with

grooves and ribs, it is obvious that only one side may be so constructed; but for general use and especially when the spike is designed for rails for heavy traffic it is desirable to 5 have both the front and rear sides formed in the manner set forth, as thereby a maximum anchorage or interlocking action between the spike and tie is had.

When the spike is penetrating the tie under the action of the blows rained upon its head, the fibers of the tie are parted by the wedge-shaped point, and as they clear the shoulders 6 they spring outward into the grooves 4 over the said shoulders, thereby 10 preventing the accidental or ready withdrawal of the spike. As the fibers spring over the shoulders 6 they are forced laterally by the inclined walls of the grooves 4 and are crowded into the latter, thereby insuring a firm 15 and positive anchoring and interlocking between the spike and tie. After the spike is driven home the fibers of the timber above the shoulder 6 will constitute a solid key or lock above the said shoulders, thereby preventing the withdrawal of the spike by the 20 vibratory action of the rails incident to traffic thereover or by the tendency of the rails to warp due to change in temperature, resulting in contraction and expansion.

30 The various grooves and depressions may be formed by stamping, milling, or casting, or in any of the ways commonly resorted to in the mechanic arts for providing similar parts, so it may enable the invention to be placed upon the market at about the same 35 cost as the ordinary spike.

The lower ends of the ribs 5 converge laterally and from the front, providing points to the penetrating ends of the ribs and a maximum amount of shoulder-surface 6 for the fibers of the tie to engage with and form a secure lock.

By constructing the spike in the manner set forth it will be longer than a spike of like 45 size with the same amount of material and will secure a firmer hold in the tie or timber and will drive as easily as any of the spikes in use, and can be used over again and straightened when bent.

50 It is to be understood that the spike will be made in various sizes and different lengths according to the size and weight of the rail or other part to be secured thereby.

Having thus described the invention, what 55 is claimed as new is—

1. A spike having spaced longitudinal grooves formed in a side thereof and having the upper extremities of said grooves inclining upwardly and outwardly in opposite directions 60 and opening out through and intersecting

with the sides adjacent to the grooved side of the spike, substantially as set forth.

2. A spike having longitudinal and parallel grooves of approximately V form in a side, said grooves deepening toward the point of 65 the spike, and communicating with each other in a rounded shoulder a short distance above the point of the spike, and being separated by an approximately V-shaped rib, the latter being beveled or pointed at its lower extremity substantially as set forth.

3. A spike provided in a side with parallel and longitudinal grooves communicating and forming a shoulder a short distance from the end of the spike, and having their upper ends 75 curving in opposite directions and terminating a short distance from the head of the spike, substantially as set forth for the purpose specified.

4. A spike having a side provided with longitudinal and parallel V-shaped grooves, separated by a V-shaped rib, said grooves gradually deepening toward the point of the spike and communicating forming a rounded shoulder, and said grooves having their upper ends 85 curving outwardly in outward directions, substantially as set forth for the purpose specified.

5. A spike having its front and rear sides similarly formed and provided with longitudinal and parallel V-shaped grooves separated by a V-shaped rib, said grooves gradually deepening toward the end of the spike and communicating forming shoulders a short distance from the point, the upper ends of the 95 grooves curving in opposite directions, substantially as and for the purpose set forth.

6. A railroad-spike, constructed substantially as set forth, having its opposite sides provided with longitudinal depressions having their origin a short distance from the head and terminating at the point, and having their end portions contracted in width and depth and merging into the said sides, and having the front and rear sides of the spike provided 100 with longitudinal and parallel grooves separated by a V-shaped rib and gradually deepening toward the point, and communicating, forming shoulders a short distance from the said point, and having the upper ends of the 105 grooves curving in opposite directions, substantially as shown for the purpose set forth.

In testimony that I claim the foregoing as my own I have hereto affixed my signature in the presence of two witnesses.

JAMES ROLLAND ELLIOTT.
